[57] CLAIM

The ornamental design for a front side of a wheel cover for vehicles, as shown and described.

DESCRIPTION

FIG. 1 is a front view of a front side of a wheel cover for vehicles according to my novel design; and.

FIG. 2 is a perspective front view of a front side of a wheel cover for vehicles according to my novel design.

The broken line showing of environment in FIG. 2 is for illustrative purposes only and forms no part of the claimed design. The hatched shading in the central hub area in FIGS. 1 and 2 is understood to represent the color black.
